US00D937299S

(12) **United States Design Patent** (10) Patent No.: **US D937,299 S**
 Varga et al. (45) Date of Patent: **** Nov. 30, 2021**

(54) **DISPLAY SCREEN WITH GRAPHICAL USER INTERFACE FOR COMMUNICATING HEALTH-RELATED MESSAGES REGARDING VENTILATED PATIENTS**

(71) Applicant: **Vyaire Medical, Inc.**, Mettawa, IL (US)

(72) Inventors: **Christopher M. Varga**, Laguna Hills, CA (US); **Hasnain Somji**, Irvine, CA (US)

(73) Assignee: **Vyaire Medical, Inc.**, Mettawa, IL (US)

(**) Term: **15 Years**

(21) Appl. No.: **29/729,194**

(22) Filed: **Mar. 24, 2020**

(51) LOC (13) Cl. **14-04**

(52) U.S. Cl.

USPC **D14/486**; D14/488

(57) **CLAIM**

The ornamental design for a display screen with graphical user interface for communicating health-related messages regarding ventilated patients, as shown and described.

DESCRIPTION

The sole FIGURE is a front view of a display screen with graphical user interface for communicating health-related messages regarding ventilated patients, showing the new design.

The broken line drawings of a display screen, text, and graphical user interface elements is included for the purpose of illustrating portions of the article and form no part of the claimed design.

1 Claim, 1 Drawing Sheet
